(57) CLAIM

The ornamental design for the garden cart handle, as shown and described.

DESCRIPTION

FIG. 1 is a three-dimensional view of a garden cart handle of a new design in a first configuration;

FIG. 2 is a top view thereof;

FIG. 3 is a right side view thereof;

FIG. 4 is a back view thereof;

FIG. 5 is a left side view thereof;

FIG. 6 is a front view thereof;

FIG. 7 is a bottom view thereof;

FIG. 8 is a three-dimensional view of the garden cart handle of FIGS. 1-7 in a second configuration;

FIG. 9 is a top view thereof;

FIG. 10 is a right side view thereof;

FIG. 11 is a back view thereof;

FIG. 12 is a left side view thereof;

FIG. 13 is a front view thereof; and,

FIG. 14 is a bottom view thereof.

The broken line showing of a portion of a handle shaft is for illustrative purposes only and forms no part of the claimed design.
